SAMUEL BOYKIN SHORT, OF HUMBOLDT, TENNESSEE.

ADJUSTABLE BULKHEAD FOR FREIGHT-CARS.

1,327,634.

Specification of Letters Patent. Patented Jan. 13, 1920.

Application filed June 20, 1919. Serial No. 305,620.

To all whom it may concern:

Be it known that I, SAMUEL BOYKIN SHORT, a citizen of the United States, residing at Humboldt, county of Gibson, and 5 State of Tennessee, have invented a new and useful Adjustable Bulkhead for Freight-Cars, of which the following is a specification.

This invention relates to adjustable bulkheads for freight cars. In loading merchandise into freight cars, in less than full car load lots, it is difficult to so arrange it that it will not be disarranged by sudden starts and stops, due to the operation of the train. 10 More especially is this the case when small lots of freight are taken on at different points along the line. In such cases it is only possible to pile the freight upon the floor of the car and trust to Providence that 15 a minimum of damage will result from the jolting of the train. When the outer surfaces of the containers are smooth, and consequently will slide easily on the floor, and on each other, and the contents are of a 20 nature such as small berries or fruits, and are easily damaged the conditions are aggravated. In some instances hurriedly constructed bulkheads of boards are erected, that in a measure serve the purpose, but 25 they are difficult to shift in order to accommodate additional lots of freight, and the train crews as a rule do not have time to handle them. Perishable articles, as a rule, 30 are shipped in refrigerator cars and the owners thereof object to their being marred by nailing.

An object of this invention is to provide a bulkhead which may be positioned within a railroad car a spaced distance from an end 40 thereof, thereby forming a compartment of suitable size for freight at hand, and which may readily be shifted to enlarge the compartment to accommodate additional quantities. 45 A further object is to provide a device as characterized, which will be economical in construction and efficient and durable in service.

With the foregoing and other objects in 50 view, the invention consists of the novel construction and arrangement of parts illustrated in the accompanying drawing, which forms a part of this specification, wherein is set forth an embodiment of the invention, 55 but it is to be understood that such changes and modifications may be resorted to as

come within the scope of the claims appended hereunto.

In the drawing wherein similar reference characters designate like parts in the several views, Figure 1, is a longitudinal section of a railroad car, showing embodiments of the invention associated therewith: Fig. 2, a front elevation of an embodiment of the invention in connection with a transverse 60 section of a car: Fig. 3, a section on line 3-3 of Fig. 2, and Fig. 4, a top plan view, removed from a car, and showing a hinged section partly open.

Referring now in detail to the drawing, 70 the reference character —10— designates a railroad car of conventional construction, comprising a floor —11—, a ceiling —12—, end walls —13— and side walls —15—. The side walls have door ways —16—. The 75 floor and ceiling are provided with opposed longitudinal grooves, or channels —17— which are covered or overlaid with metallic bars —18—, —19— which are provided with a plurality of spaced perforations —20—. 80 The bars 18, are sunk in the floor, lying flush with the surface thereof, in order that they will offer no obstruction to the movement thereover. A bulkhead —21—, which may be of any suitable size, or desired construc- 85 tion is provided on its lower edge with projection or spurs —22— adapted to be engaged in selected perforations in the lower bars 18, and with slidable bolts —23— adapted to be projected into perforations in 90 the upper bars 19. With the spurs and bolts engaged as described, the bulkhead is securely held against displacement. It is to be understood that as many points of engagement, both upper and lower, may be 95 provided as may be necessary and that while illustrated as being in vertical alignment they need not necessarily be so, as they may as well be in staggered relationship, and there may be more points of engagement at the 100 floor line than there are at the roof or vice versa. Preferably the bulkhead is provided with a hinged section —25—, and it is provided with sliding bolts —26—, —27— at the bottom and at the top, these bolts are operatively connected by means of links —28— with a hand lever —29— being connected thereto respectively on each side of its pivotal point. The bolts 23 are each operatively connected by means of links —31— with 105 hand levers —32—. The hand levers may each be provided with a hinged hasp —33—

110

which is provided with a slot —34— adapted to be placed over a staple —35— where it may be secured by suitable means such as a padlock or seal, such as is usually used for sealing cars, or both. In this way a sealed compartment may be provided that may only be opened at a predetermined point. While as previously stated the bulkhead may be of any desirable construction, as herewith illustrated it consists of a plurality of vertically arranged T irons and angles, certain of which —40— are disposed so that the flanges thereof face the merchandise while the others as —41— are reversely positioned, and carry the locking devices. The angles —42— are disposed at the contiguous edges of the body and the hinged section and are connected by means of hinges —43—. The respective T irons and angles of the body portion and hinged sections are connected by suitably spaced members such as rods —44— which extend through and are suitably secured in the stems of the respective irons.

From the foregoing description it will be seen that I have produced a bulkhead that may readily be adjusted at any point intermediate the length of the car, which will hold the freight securely against displacement, which will afford ready access to retained freight, which may be easily shifted to compensate for the removal of, or to provide room for additional freight, and that by its use locked compartments may be provided that will in nowise interfere with the free circulation of air in refrigerator cars. Having thus described my invention so that those skilled in the art pertaining thereto can make and use the same.

I claim:

1. A bulkhead as characterized, comprising a main section and a door section in

hinged relation thereto, said sections each comprising spaced intersecting members, certain of the members of the main section having projections adapted to be engaged with the floor of a car, and with locking elements adapted to be projected into engagement with the roof of the car, and said door section having locking elements adapted to be projected into engagement with both the floor and the roof.

2. A movable bulkhead comprising a plurality of vertically disposed T irons their stems having a plurality of aligned perforations, transverse members secured in said perforations holding the irons in spaced relationship, certain of said irons arranged with their angles facing forward and being provided with engaging points projected from their lower ends adapted to be engaged in the floor of a car and having slideable bolts on their faces adapted to be projected beyond their upper ends.

3. A movable bulkhead comprising a main section and having a hinged door section, each consisting of a plurality of vertically disposed T irons the stems of which are provided with aligned perforations, transverse members extended through said perforations and holding said irons in spaced relationship, certain of the irons being so arranged that their angles face forward, the angles of the others facing the rear, those in the main section which face forward having engaging points projecting from their lower ends and having sliding bolts on their faces projecting beyond their upper ends and that iron which faces forward in the door section having a sliding bolt at each end thereof adapted to be projected beyond the ends thereof.

SAMUEL BOYKIN SHORT.
